R. M. RELLHEN

TEXTILE FABRIC OR SIMILAR ARTICLE

Filed Sept. 12, 1927

Inventor:
Ralph M. Rellhen,
By Wilkinson, Husley, Byron & Knight,
Atlys.

UNITED STATES PATENT OFFICE.

RALPH M. RELLIHEN, OF CHICAGO, ILLINOIS, ASSIGNOR TO MARSHALL FIELD & COMPANY, OF CHICAGO, ILLINOIS, A CORPORATION OF ILLINOIS.

DESIGN FOR A TEXTILE FABRIC OR SIMILAR ARTICLE.

Application filed September 12, 1927. Serial No. 23,391. Term of patent 3½ years.

To all whom it may concern:

Be it known that I, RALPH M. RELLIHEN, a citizen of the United States, residing at Chicago, in the county of Cook and State of Illinois, have invented a new, original, and ornamental Design for Textile Fabric or Similar Articles, of which the following is a specification.

The accompanying drawing, forming part of this specification, is a view of a portion of a textile fabric bearing the design.

I claim:

The ornamental design for a textile fabric or similar article as shown.

RALPH M. RELLIHEN.
